UNITED STATES PATENT OFFICE.

EZRA TIMM, OF OSCEOLA, NEBRASKA.

SCREW-CUTTING STOCK AND DIE.

SPECIFICATION forming part of Letters Patent No. 674,105, dated May 14, 1901.

Application filed November 8, 1900. Serial No. 35,844. (No model.)

To all whom it may concern:

Be it known that I, EZRA TIMM, a citizen of the United States, residing at Osceola, in the county of Polk and State of Nebraska, have 5 invented certain new and useful Improvements in Screw-Cutting Stocks and Dies; and I do declare the following to be a full, clear, and exact description of the invention, such as will enable others skilled in the art to which 10 it appertains to make and use the same.

This invention relates to improvements in screw-cutting stocks and dies for screw-threading pipes, rods, and other like objects.

The invention has for its object to provide 15 a die-stock which may be quickly applied and removed and accurately adjusted, to provide improved means for securing the dies to the stock to adapt the same to be easily and expeditiously attached and detached, to provide 20 for the use of auxiliary dies in connection with the main dies for threading smaller objects than said main dies are adapted for, and to generally simplify and improve the construction and increase the practical efficiency 25 of devices of this character.

With this and other minor objects in view the invention consists of certain novel features of construction, combination, and arrangement of parts, as will be hereinafter 30 more fully described, and particularly pointed out in the appended claims.

In the accompanying drawings, Figure 1 is a perspective view of a screw-threading device embodying my invention, showing the 35 jaws of the stock open. Fig. 2 is a sectional view on line 2 2 of Fig. 1, showing the jaws closed. Fig. 3 is a section through one of the jaws and main dies on line of the dovetailed rib and dowel-pin. Fig. 4 is a front 40 elevation of one of the die members. Fig. 5 is a rear perspective view thereof.

Referring now more particularly to the drawings, the numerals 1 and 2 represent the semicircular jaws of an ordinary split die-stock, each of which is provided with a socket 3 for the reception of an operating-handle 4, whereby the device is turned on the pipe or rod to be threaded. At one side of the stock the meeting ends of the jaws are hinged or 45 pivotally connected by a pivot pin or bolt 5, and the opposite or free ends of the jaws are provided with spaced pairs of lugs 6 and 7.

Between the lugs 6 is pivoted a locking-bolt 8, which is adapted to swing down between the lugs 7 and to be held in such position to 55 lock the jaws closed by a wing-nut 9, tapped thereon and adapted to bear upon the outer faces of said lugs 7. When it is desired to open the jaws, the nut is loosened and the bolt thrown back, as shown in Fig. 1. To prevent 60 the bolt from moving too far back, the pivoted end thereof is formed with a cam-head 10, which binds upon the jaw and also abuts against a stop-shoulder 11, thereby preventing the bolt from passing rearward of a position perpendicular to its axis. The pivot pin or bolt 5 is preferably tapered, so that it may be adjusted to compensate for wear and provide for a close fitting at all times of the 65 hinged end of the jaws.

The dies 12 and 13, which for convenience of description will be hereinafter termed the "main" dies, are adapted to be secured to the jaws to open and close to admit the pipe or other object to be threaded between them 75 and to release said pipe and are provided with the thread-cutting portions or die-faces 14. These die-faces extend part way across the meeting faces of the main dies and terminate alongside dovetailed sockets 15, occupying the remaining transverse extent of said meeting faces. In these sockets are 80 slidably fitted dovetailed auxiliary dies 16, whose thread-cutting portions or die-faces are gaged to thread smaller-sized objects than 85 the said die-faces 14, and said auxiliary dies are adjustable outwardly through the medium of tapered adjusting-screws 17. When it is desired to thread pipes or rods of smaller diameter than the main dies are designed for 90 threading, the auxiliary dies are slipped into the sockets 15, thus adapting the device to be quickly and conveniently fitted for threading rods or pipes of different sizes.

The main dies 12 and 13 are secured in such 95 a manner as to facilitate their application and removal, and to this end each of said dies is provided on its convex face with a dovetailed rib 18 and dowel-pin 19, located at or adjacent to opposite ends thereof. The 100 rib 18 is adapted to enter a dovetailed groove 20 and the dowel-pin 19 to enter a seat-groove 21, formed on the inner face of the co-operating jaw of the stock, the said groove 20 being

located at the free end of the jaw and the seat-groove 21 at the hinged end thereof. To apply the main die to the jaw, the inner end of the rib is first slipped into the groove 20 5 and slid downward until the pin 19 comes in line with the upper end of the seat-groove 21, when the pin is fitted in said seat-groove and the die then slid downward into proper position. By this construction a simple and se- 10 cure fastening is provided and the main die adapted to be readily and quickly connected to and disconnected from the jaw.

From the foregoing description, taken in connection with the accompanying drawings, 15 the construction, mode of operation, and advantages of the invention will be readily understood, and it will be seen that a convenient and efficient form of threading implement is provided.

Changes in the form, proportion, and minor details of construction may be made within the scope of the invention without departing from the spirit or sacrificing any of the advantages thereof.

Having thus fully described my invention, what I claim, and desire to secure by Letters Patent, is—

1. In a screw-threading device, the combination of a stock having hinged segmental

jaws provided on their inner faces with upper and lower grooves, the upper grooves being dovetailed, and segmental dies having dovetailed ribs to engage the upper grooves and dowel-pins to engage the lower grooves, substantially as set forth.

2. In a screw-threading stock and die, the combination of a stock having hinged seg- 35 mental jaws provided on their inner faces with upper and lower grooves, the upper grooves being dovetailed, segmental dies hav- 40 ing dovetailed ribs to engage the upper grooves, and dowel-pins to engage the lower grooves, said dies being also provided with a screw-threading surface extending part way 45 across the face thereof, a dovetailed socket occupying the remaining extent of said face and open to the exterior on one side, an aux- 50 illary screw-threaded die having dovetailed portions to fit within said socket, and a tapered screw for securing said auxiliary die, substantially as described.

In testimony whereof I have hereunto set my hand in presence of two subscribing witnesses.

EZRA TIMM.
